UNITED STATES PATENT OFFICE.

CHARLES MORLET AND EUGENE DUPUIS, OF NEW YORK, N. Y.

REPEATING-WATCH.

SPECIFICATION forming part of Letters Patent No. 325,854, dated September 8, 1885.

Application filed March 7, 1884. (No model.)

To all whom it may concern:

Be it known that we, CHARLES MORLET and EUGENE DUPUIS, both of the city, county, and State of New York, have invented a new and Improved Repeating-Watch, of which the following is a full, clear, and exact description.

This invention relates to certain new and useful improvements in that class of watches known as "repeating-watches," and which are provided with mechanism for striking bells, wires, or metal plates in such a manner as to indicate the time by a number of strokes for the hours and a number of strokes for the minutes.

The object of our invention is to materially simplify the construction of such repeating-watches, whereby fewer parts are required, the striking mechanism can be driven from the mainspring of the watch, the striking mechanism can easily be removed from the watch, and the cost of these watches will be materially reduced.

The invention consists in the combination, with a watch, of a repeating mechanism and means for operating the repeating mechanism from the mainspring of the watch.

The invention further consists in the combination, with a watch and the repeating mechanism, of means for throwing the repeating mechanism in gear with the mainspring at the same time that the repeating mechanism is started.

The invention further consists in various parts and details and numerous combinations of the same, as will be fully described, and set forth hereinafter.

Reference is to be had to the accompanying drawings, forming part of this specification, in which similar letters of reference indicate corresponding parts in all the figures.

Figure 1 is a face view of our improved striking mechanism for a repeating-watch. Fig. 2 is a face view of the detachable plate carrying the striking mechanism, parts of the mechanism being omitted to show other parts more clearly. Fig. 3 is an inside view of the plate below the one carrying the repeating mechanism. Fig. 4 is a face view of the plate directly below the dial, showing the winding mechanism and the mechanism for connecting

the mainspring with the repeating device, parts being broken out and others shown in section. Fig. 5 is a cross-sectional view of the clock-work on the broken line $xx'xx'xx$, 55 Fig. 1. Fig. 6 is a cross-section on the line $yy'y'y$, Fig. 1. Fig. 7 is a sectional view on the line $ww'w'w$, Fig. 1. Fig. 8 is a plan view of the under side of the wheel for operating the middle spindle. 60

Referring to Fig. 4, a beveled pinion, A, is mounted on the winding-stem A' and engages with the beveled cog-wheel A², which engages with the cog-wheel A³, adapted to engage with a cog-wheel, B, on the casing, in which the free end of the mainspring is fastened.

A pivoted pawl, B', is adapted to engage with the cogs of the wheel B, and is pressed against the said cogs or teeth by a spring, B², resting on the outer edge of the pawl. The 70 said pawl is provided with a shoulder, B³, against which the end of the spring B² can rest under certain circumstances, as will be described hereinafter. The pawl B' is provided with a projection, B⁴, against the inner 75 edge of which a sliding pin, B⁵, rests, the opposite end of which pin is beveled and adapted to pass in between the cogs of the wheel A³, the said pin being adapted to slide in a suitable guide aperture in the frame of the watch. 80 The pawl B' is also provided with a projection, B⁶, which is adapted to act on one end of a pivoted lever, C, the opposite end, C', of which rests against a hub or spindle, A⁴, on which the cog-wheel A³ turns. A suitable spring is 85 provided for pressing the wheel A³ against the rim of the wheel B on the spring-easing, as is usual in stem-winding watches.

A push-pin, D, projects from the edge of the works and is formed on the angle of an angle 90 spring-lever, D', that will be described hereinafter, and the said push-pin D also acts on the projection B⁴ of the pawl-lever B'; and if the said push-pin is pushed inward the end projection, B⁴, of the pawl-lever B' is pressed 95 inward, and the outer end of the pawl-lever is moved outward and disengaged from the teeth of the cog-wheel. By the said outward movement of the inner end of the pawl-lever B' the end of the spring B² is caused to engage with the shoulder B³ of the said pawl-lever, and thus lock the pawl-lever in place, 100

disengaged from the teeth of the wheel B, as shown. If the pawl-lever is moved inward by the push-pin, as described, its projection B⁶ will act on the end of the lever C and cause the opposite end, C', of the said lever C to press on the hub A⁴ of the wheel A³ and move the wheel A³ from the wheel B, whereby the said wheels A³ and B will be disengaged and will remain so as the pawl B' is locked in position 10 by the spring B². At the same time the beveled end of the bolt or pin B⁵ is moved in between two teeth of the wheel A³ and locks the same in place.

If the parts are all in the positions just described and shown in Fig. 4, and the winding-stem A' is turned, the teeth of the wheel A³, acting on the beveled inner end of the bolt B⁵, will force the said bolt outward and cause its outer end to press the projection B' of the pawl-lever B' outward, thereby pressing the opposite end of the lever in between the teeth of the wheel B, the end of the spring B² snapping over the shoulder B³ and resting on the edge of the pawl-lever above the shoulder.

By the above-described movement of the pawl-lever B' the end of the lever C is released, thus permitting the spring provided for this purpose to throw the wheel A³ in gear with the wheel B, and thus permitting the spring to be wound by turning the winding-stem A', which turns the pinion A, the beveled cog-wheel A², the cog-wheel A³, and the cog-wheel B. It is thus seen that as soon as the push-pin D is pushed inward the mainspring is disengaged from the winding device, and as soon as the winding-stem A' is turned, the winding apparatus is thrown in gear with the mainspring.

As stated above, the push-pin D is formed at the angle of an angular spring-lever, D', secured on the inner surface of a plate, D², the free end D³ of the said spring being beveled and resting on a bridge, D⁴, held on the under side of the plate D². The lower slightly rounded or beveled end of an upright shaft or spindle, E, rests on the bridge D⁴, and passes through the plate D², and on the said shaft E is loosely mounted a sleeve, a, on which is loosely mounted a cog-wheel, F, and on a sleeve, a', held to turn with the shaft or spindle E, is rigidly mounted a wheel, G, provided with twelve teeth, G', which occupy about one-third of the circumference of said wheel.

Above the wheel G a pinion, J, is rigidly mounted on the sleeve a', and above the pinion J a curved arm, I, is loosely mounted on the shaft E, and is connected by a pin or rivet, I', with the pinion J. The upper end, E', of the shaft E, which is of less diameter than the lower part, passes through an aperture in the free end of a spring, E², which is secured on the plate D², the free end of the said spring E² resting on the shoulder formed on the upper end of the shaft E.

The wheel G is provided at its under side

with a downwardly-projecting tooth, G², adapted to pass in between and engage with the teeth of the cog-wheel F. The cog-wheel F engages with the cog-wheel F', driven by the mainspring-spindle j'. The cog-wheel F' engages with a pinion, F², made integral with another cog-wheel, F³, engaging with a pinion, F⁴, made integral with a cog-wheel, F⁵, engaging with a pinion, F⁶, provided with an escape-wheel, F⁷, which engages with an anchor, F⁸, on which a swinging weighted arm, F⁹, is mounted, as shown in Figs. 1 and 7. The pinions F², F⁴, and F⁶ and anchor F⁸ are not mounted on arbors held between two plates 80 or bridges, as is usual in watches, but are mounted on pivots f, projecting upward from the plate D².

The object of the train of gearing just described is to prevent the wheel F from revolving too rapidly, as will be fully set forth hereinafter.

On two spindles, h and h', projecting from the surface of the plate D², two stepped or toothed cams, H and H', are mounted, the said stepped cams gradually increasing in diameter from the first to the last step. On the spindle h is rigidly mounted a star-wheel, H², having eleven teeth, and the stepped cam H is provided on its under side with a tooth, 95 h², adapted to act on the teeth of the star-wheel H², so that for every revolution of the stepped cam H the stepped cam H' will be moved one-eleventh of a revolution. A locking-spring, H³, is secured on the plate D², and its free end rests against the teeth of the star-wheel H² to hold the said wheel in place.

Two curved arms, J' and J², rigidly united and held almost parallel, are both pivoted on a spindle, j, the curved arm J' having a rack, J³, formed in one edge at its free end, and the said rack being adapted to engage with the teeth of the pinion J, which is mounted rigidly on the sleeve a' of the spindle or shaft E. A prong, J⁴, formed at the free end of the arm J², is adapted to rest on the steps of the stepped or toothed cam H'.

An elliptical or like frame, K, is pivoted on a spindle or pivot, k, and is provided with a rack, K², having eleven teeth, which rack is arranged almost diametrically opposite the spindle or pivot k. The said frame K is also provided with a prong, K³, the end of which is adapted to rest on the steps of the toothed or stepped cam H. The frame K is provided with a shoulder, K⁴, against which the free end of the arm I is adapted to rest. A stoppin, l, projects down from the under surface of the frame K, and is adapted to strike against a pin, m, projecting upward from the surface of the plate D². A spring, L, secured at one end on the plate D², has its opposite end connected with the arm J' a short distance from the pivot or pintle j, so that the spring will have the tendency to throw the arms J' J² in the direction of the arrow x'. A spring, M, having one end secured on the

plate D⁵, has its free end resting against a pin secured on the frame K a short distance from the pivot k, which spring M has the tendency to throw the frame K in the direction of the 5 arrow y'. Two circular spring-wires, N and O, each have one end secured on the plate D⁵, as shown at o, Fig. 1. Two hammers, N' and O', are pivoted to the plate D⁵. A spring, P, acts on the hammer N', at that end opposite the 10 one provided with a head, and presses the said end of the hammer against the stud P' on the plate D⁵, thereby pressing the head in the direction toward the corresponding spring, N. A spring, Q, acts on the hammer O' and presses 15 its head in the direction toward the spring O, and presses the opposite end of the said hammer O' against the stud Q' on the plate D⁵. The hammer O' is provided at the end opposite the one with a head with a projection, R, 20 against which the teeth G' of the wheel G can act. The hammer N' is provided with a tooth, S, against which the teeth of the rack K' of the frame K can act. The hammer O' serves to strike the number of hours on the spring 25 O, and the hammer N' serves to strike the minutes on the spring N. The hammer N does not indicate each single minute; but each stroke corresponds to five minutes.

The operation is as follows: If the push-pin 30 D is pushed inward and pushes the spring-lever D' inward, the beveled end D³ of the said lever D', acting on the spindle E, pushes the same upward, whereby the wheel G will be raised, and the tooth G² on the under side 35 of the said wheel G will be disengaged from the teeth of the wheel F, thus permitting the springs M and L to throw the frame K in the direction of the arrow y', and the arms J' and J² in the direction of the arrow x'; but the 40 prongs K² and J⁴ of the frame K and the arm J², respectively, strike against the steps of the cams H and H', thereby checking the movements of the frame K and the arms J' J². By the movement in the direction of the arrow x' 45 of the arm J', its rack J³ revolves the pinion J, and thereby turns the wheel G, connected with the pinion J, in direction of the arrow w'. The cams H and H' are operated by the clock mechanism, the cam H making one revolution every hour and the cam H' one revolution every twelve hours. It is evident that 50 at different times of the day the cams H and H' are in different positions in relation to each other and to the ends of the prongs J⁴ and K². Thus at twelve o'clock that edge of the cam H' the shortest distance from the pivot h' will 55 face the end of the prong J⁴, thus requiring the arms J' and J² to move a greater distance before the end of the prong J⁴ rests against the edge of the cam H'. At or near the end 60 of the hour the cam H is in such a position that that part of its edge which is the shortest distance from the pivot h will face the prong K² of the frame K, thus requiring a greater movement of the frame K in the direction of the arrow y', to cause the end of the prong K²

to rest on the edge of the cam H. At one or two o'clock the movement required to bring the prong J⁴ against the edge of the cam H' will be least, and the throw of the arm J' will 70 be correspondingly small. A few minutes after the hour the distance between the edge of the cam H and the end of the prong K² will be least, and the distance that the prong K² must move to come in contact with the 75 edge of the cam H will be least, and the throw of the frame K will be decreased in proportion. Thus the cams H and H' always limit the throw of the frame K and the arms J' and J², according to the time. If the frame 80 K, for instance, is thrown but a short distance in the direction of the arrow y' and moves back in the inverse direction of the arrow y', but a few teeth of the rack K' will strike against the tooth S of the hammer N', and the hammer 85 will strike but a few times. If the throw of the frame K in the direction of the arrow y' is very great, more teeth of the rack K' will strike against the tooth S of the hammer, which strikes the spring-wire N oftener. In a like 90 manner, the number of times that the hammer O' strikes the spring-wire O is governed by the distance that the prong J⁴ must move to come in contact with the rim of the cam H'. After the pin D has been pushed inward the spring-lever D' snaps outward and from under the lower end of the spindle E, thus permitting the spring E² to force the spindle E downward and engage the tooth G² of the wheel G with the teeth of the cog-wheel F again. As has 95 been stated, by pushing the push-pin D inward the pawl B' is disengaged from the ratchet-wheel B, which is mounted on the arbor or spindle to which the mainspring is fastened, thus permitting the spring to revolve the said 100 wheel in the inverse direction of that in which it is revolved by winding the spring. The spring is then held at the rim of the spring-casing and acts on the central spindle, thereby also revolving the wheel F'. If the pawl 105 B should not be disengaged from the wheel B, the spring could not revolve the spindle on which it is wound. The wheels B and F' are revolved in the direction of the arrow v', and the wheel F' acts on the wheel F. As the wheel 110 F does not afford resistance for the spring, the train of gearing shown in Fig. 7 is provided, which prevents the spring from revolving the wheel F' too rapidly. The wheel F', if revolved from the spring-spindle, revolves the wheel F 115 in the inverse direction of the arrow w'; and as the tooth G² connects the wheel G with the wheel F the said wheel G will also be revolved in the inverse direction of the arrow w', and its teeth G' will successively strike against the 120 tooth R of the hammer O', causing the hammer to strike the wire O, and thus produce the desired sound. By the movement of the wheel G in the direction of the arrow w' the free end of the arm I has been moved a greater or 130 less distance from the shoulder K³ of the frame K, and by the time that the last tooth, G', has

acted on the tooth R of the hammer O' the end of the arm I will rest against the shoulder K³ of the frame K; and as the wheel G continues to move in the inverse direction of the arrow w' the frame K will be moved in the direction of the arrow y', and the teeth of the rack K' will strike against the tooth S of the hammer N', and thus cause the hammer N' to strike the wire N, each stroke corresponding to five 10 minutes past the hour. The frame K moves in the inverse direction of the arrow y' until its pin l strikes against the pin m on the plate D⁵, whereby the entire ringing mechanism or repeating mechanism is stopped automatically. As soon as the winding stem is turned 15 the wheel A³ is thrown in gear with the wheel B, and the pawl B' is engaged with the ratchet-wheel B, thus preventing the spring from acting on the central spindle and revolving 20 the same, and now the spring must act on the rim of its casing, as the central spindle is held by the pawl B', which engages with the ratchet-wheel B.

That I may be fully understood I will repeat the action in brief. By pressing the 25 push-pin D inward the cog-wheel B, connected with the spindle on which the mainspring is fastened, is released, and at the same time the wheel G is disengaged from the ratchet-wheel F, permitting the frame K and the arms J' J² to be thrown back until their prongs J¹ and K² rest against the teeth of the cams H' and H. The mainspring can now revolve its 30 central spindle or stem as the wheel B is released, and the said mainspring can revolve the wheel F and the wheel G, thereby causing the teeth G' of the wheel G to operate the hammer O; and when the hammer O has completed striking the hours, the arm I rests 35 against the shoulder K³ of the frame K and moves the frame K in the inverse direction of the arrow y' and causes the teeth of its rack K' to act on the hammer N', causing the same to strike the spring-wire N until the pin l rests against the pin m.

In place of providing the tooth G² on the under side of the wheel G in such a manner that it can engage with the teeth of the wheel F, the tooth G² can be arranged in a different 50 manner, and can be adapted to pass into a recess or aperture in the upper surface of the wheel F.

Heretofore repeating-watches have been provided with separate springs for operating 55 the repeating mechanism; but in our improved repeating-watch the mainspring is used for operating the repeating mechanism, and the means which have been described above are used for operating the repeating mechanism from the central spindle of the mainspring, the usual clock-work mechanism being operated from the outer end of the mainspring, which acts on the casing of the mainspring. Furthermore, the entire repeating mechanism 60 is held on the plate D⁵, which can easily be detached, so that the other parts of the works

need not be disturbed while removing the striking or repeating mechanism, and at the same time that the repeating mechanism is thrown back by its springs into the position 70 corresponding to the hour and minute the connection of the mainspring and repeating mechanism is made.

Having thus fully described our invention, we claim as new and desire to secure by Letters 75 Patent—

1. The combination, with a watch, of a repeating mechanism, gearing for operating the repeating mechanism from the mainspring, and mechanism, substantially as set forth, for 80 disengaging the ratchet-wheel on the spindle of the mainspring from its pawl in the operation of starting the repeating mechanism, substantially as herein shown and described.

2. The combination, with a watch, of a repeating mechanism, a lever or spring for starting the repeating mechanism, gearing for operating the repeating mechanism from the main-spring of the watch, mechanism, substantially as set forth, for disengaging the pawl from the 90 cog-wheel mounted on the spindle of the main-spring, and mechanism, substantially as set forth, for disengaging the winding mechanism from the said cog-wheel, substantially as herein shown and described.

3. The combination, with a watch, of a repeating mechanism, gearing for operating the repeating mechanism from the mainspring of the watch, mechanism, substantially as set forth, for disconnecting the winding gear from the winding cog-wheel on the spindle of the mainspring, mechanism, substantially as set forth, for throwing the pawl from the said cog-wheel, and mechanism, substantially as set forth, for throwing the said pawl back against 105 the cog-wheel when the winding mechanism is turned, substantially as herein shown and described.

4. The combination, with a watch, of a repeating mechanism, gearing for operating the 110 said repeating mechanism from the mainspring of the watch, a device for starting the repeating mechanism, the pawl B' for locking the cog-wheel B on the spindle of the main-spring, which pawl has a shoulder, B³, and of 115 the spring B², substantially as herein shown and described.

5. The combination, with a watch, of a repeating mechanism, gearing for operating the 120 said repeating mechanism from the mainspring of the watch, a device for starting the repeating mechanism, the pawl B' for engaging with the cog-wheel B on the spindle of the main-spring, which pawl has a projection, B⁶, the lever C, and the cog-wheel A³, engaging with 125 the winding cog-wheel B, substantially as herein shown and described.

6. The combination, with a watch, of a repeating mechanism, means for operating the 130 said repeating mechanism from the mainspring of the watch, a device for starting the repeating mechanism, the pawl B' for engaging with

the winding cog-wheel B on the spindle of the mainspring, which pawl has projections B⁶ and B⁴, the lever C, the cog-wheel A³, engaging with the winding cog-wheel B, and the bolt or pin B⁵, having a beveled end adapted to engage with the teeth of the cog-wheel A³, and having its opposite end resting against the inner edge of the projection B⁴ of the pawl

B', substantially as herein shown and described.
